US0D1085652S

(12) **United States Design Patent** (10) **Patent No.:** **US D1,085,652 S**
(45) **Date of Patent:** **** Jul. 29, 2025**

(54) **BELT**

(71) Applicant: **Dongguan Paidaxing Technology Co., Ltd**, Dongguan (CN)

(72) Inventor: **Lizhi Zhang**, Dongguan (CN)

(73) Assignee: **Dongguan Paidaxing Technology Co., Ltd**, Dongguan (CN)

(**) Term: **15 Years**

(21) Appl. No.: **29/985,672**

(22) Filed: **Jan. 16, 2025**

(30) **Foreign Application Priority Data**

Dec. 6, 2024 (CN) 202430776011.3

(51) **LOC (15) Cl.** **24-04**

(52) **U.S. Cl.**

USPC **D24/190**
